UNITED STATES PATENT OFFICE.

ARTHUR PAULSON, OF NEW YORK, N. Y., ASSIGNOR, BY DIRECT AND MESNE ASSIGNMENTS, TO HARVARD HOLDING CORPORATION, OF NEW YORK, N. Y.

EXTENSIBLE LINK.

Application filed May 19, 1925. Serial No. 31,453.

My invention relates to an extensible link for supporting the dropfront of cabinet files of the type shown in my copending application for cabinet files, Serial Number 5 746,560, filed October 29, 1924.

In the said application the extensible link consists of two strips of light metal pivoted together at one end of each and having the other ends secured to a back and a drop front respectively.

In practice it has been found that when the front is pulled out violently the joint between the strips occasionally rises above the dead-center position so as to obstruct the closing of the file. Furthermore if the front be closed violently it has been found that the extensible link will sometimes buckle in a transverse plane at the joint of the strips and fail to function.

It is an object of my invention to so modify the extensible link as to obviate these defects and still maintain the simplicity of structure and ease of manufacture.

I have shown in the drawing and will now describe the preferred embodiment of my invention, but it is to be understood that various changes may be made within the scope of my invention and that I do not intend to be limited except as specified in the claims.

Referring to the drawing, the figure shows a view of an extensible link, constructed according to my invention, and taken from the attaching side and in opened position.

The extensible link consists of 2 relatively long strips of light metal 1 and 2 of arcuate shape. The strip 1 is flat and has an opening 6 for engagement with a pivot on a movable member (not shown). The strip 40 2 is flat for the major part of its length but is provided at its end with portion 3 bent at right angles to the strip and having an attaching flange 4 bent parallel to the strip. The flange 4 has an opening 5 for engage-

ment with a pivot on a fixed member (not shown). At their intermediate ends the strips 1 and 2 are pivoted together as at 8. The strip 2 at its intermediate end is provided with a flange 7 formed by bending over a portion of the metal and adapted to engage the strip 1 when the extensible link is in the extended position shown.

When the extensible link is operated to close, the joint 8 descends and the two strips 1 and 2 approach, the offset 3, providing sufficient space for the movable member. The flange 7 provides sufficient stiffness at the joint to overcome the tendency to buckle transversely which is found at the wide open position. When the extensible link has been slightly closed, this tendency disappears and hinge closes freely. When the extensible link is opened the bottom of the channel formed by the flange 7 engages the lower edge of the strip 1 and prevents overrunning of the fully opened position.

I claim:

1. An extensible link comprising two substantially flat arms pivoted to each other near an end of each, one of the arms being of arcuate shape and having an end bent over laterally to provide a channel with rear and side walls adjacent the pivot to receive the other arm in one of its positions in such manner that an edge of the 75 said other arm engages the rear wall in approximately parallel relation.

2. An extensible link comprising two substantially flat arms pivoted to each other near an end of each, one of the arms having an end bent over laterally adjacent the pivot to provide a channel with rear and side walls adapted to receive the other arm in one of its positions in such manner that an edge of the said other arm engages the 85 rear wall in approximately parallel relation.

ARTHUR PAULSON.
